FACETED GAME BALL

André Dufaud, 20, Rue de la Republique
Privas, France

Filed May 4, 1973, Ser. No. 357,517

Claims priority, application France Nov. 15, 1972

Term of patent 14 years

Int. Cl. D21—01

U.S. Cl. D34—5 GP

FIG. 1

FIG. 2

FIG. 1 is a perspective view of a faceted game ball showing my new design; and

FIG. 2 is a side elevational view thereof, the side opposite being substantially identical.

I claim:

The ornamental design for a faceted game ball, as shown and described.
